UNITED STATES PATENT OFFICE

173,170

GAME BOARD

Harry Polakoff, New York, N. Y.

Application December 7, 1953, Serial No. 27,946

Term of patent 3½ years

(Cl. D34—5)

To all whom it may concern:

Be it known that I, Harry Polakoff, a citizen of the United States of America and a resident of the city of New York, in the county of New York and State of New York, have invented a new, original, and ornamental Design for a Game Board, of which the following is a specification, reference being had to the accompanying drawing, forming a part thereof.

The figure is a plan view of a game board showing my new design.

The game board is of conventional thickness.

I claim:

The ornamental design for a game board, substantially as shown and described.
